UNITED STATES PATENT OFFICE.

HARRY A. MACCLYMENT, OF HAMMOND, INDIANA, AND WILLIAM F. SIMS, OF CHICAGO, ILLINOIS.

MOLD FOR SHAPING ICE.

SPECIFICATION forming part of Letters Patent No. 678,017, dated July 9, 1901.

Application filed July 27, 1900. Serial No. 24,978. (No model.)

To all whom it may concern:

Be it known that we, HARRY A. MACCLYMENT, of Hammond, Lake county, Indiana, and WILLIAM F. SIMS, of Chicago, in the 5 county of Cook and State of Illinois, have invented certain new and useful Improvements in Molds for Shaping Ice; and we do hereby declare that the following is a full, clear, and exact description thereof, reference being had 10 to the accompanying drawings, and to the letters of reference marked thereon, which form a part of this specification.

This invention relates to improvements in ice-molds of that class whereby irregular 15 pieces of ice are formed into symmetrical shape for use in iced beverages or on the table.

The invention consists in the matters hereinafter described, and more particularly pointed out in the appended claims.

20 In the drawings, Figure 1 is a plan view of an ice-mold embodying the improvements herein-
after set forth. Fig. 2 is a side elevation of the mold. Fig. 3 is an end elevation. Fig. 4 is a view in longitudinal section, partially broken away, 25 showing the two parts of the mold in engagement. Fig. 5 is a vertical section on line 5 5 of Fig. 4, looking toward the center of the device. Fig. 6 is a vertical section on line 6 6 of Fig. 4, looking toward the outer end of the 30 half-mold. Fig. 7 is a horizontal section on line 7 7 of Fig. 4, showing the face and discharge-pipes. Fig. 8 is a view, partially in vertical section, of another form of the device. Fig. 9 is a section showing a detachable mold-face.

The device, in general terms, comprises a two-part mold provided with means whereby one or both of said parts may be heated. Suitable connections may be provided, if desired, 40 between the two parts whereby they can easily be brought into accurate engagement, thereby closing the mold. The mold is preferably of a size that will make pieces that can be readily inserted in tumblers or 45 glasses; but any decorative designs for the table may be used.

A preferable form of mold which embodies the invention consists of a frame to which one of the mold parts is secured and on which 50 the other of said parts has sliding connection, whereby it may be made to close on said fixed

part. Means to heat one or both of said parts are also provided in the mold. The sliding connection may take the form of guide rod or rods parallel to the frame on which the 55 movable part of the mold slides and in alignment with the fixed part, or the guide rod or rods may be perpendicular to the frame. In this instance the frame acts as a base, on which the fixed part of the mold is secured, 60 the guide rod or rods in this case being a vertical standard or standards, on which the movable part of the mold slides in vertical alignment with the fixed part. A convenient means for heating either or both parts con- 65 sists in causing hot water to circulate through pipes or chambers across the rear of the face of the mold in contact therewith. Another means which is desirable is to electrically heat metal conductors which are in contact 70 with the rear of the mold-face. Obviously a current of hot air or a gas jet or flame in contact with the mold may be used, and we do not restrict ourselves to any particular form of mold or device for heating same ex- 75 cept as set forth in specific claims.

Referring to the drawings, A in Figs. 1, 2, 3, 4, 5, 6, and 7 represents a half-mold or part of a mold of a horizontal type, which embodies the essential features of the invention. 80 Said half-mold contains a hollow chamber a^5 , formed by a cylindric side wall a^1 , an end wall a^2 , and the mold-face a^3 . The edge a^4 of the mold-face is preferably sharp, as shown. Within the chamber a^5 and close to the edge 85 a^4 is a tubular ring D, whose external diameter is slightly less than the internal diameter of the chamber. Said tubular ring is provided with orifices d , which open or point directly toward the said mold-face a^3 and the 90 rear faces of the portion of the walls which form the cutting edge. Said ring is connected with a feed-pipe d' , which leads to any convenient hot-water supply. E is an efflux-pipe to carry the water from the chamber. The 95 standard B is shown as provided with two arms b , extending horizontally from opposite sides thereof. At the opposite end of the frame C a standard B', with arms b' , similarly disposed, is suitably secured. Horizontal 100 rods b^2 , parallel to the longitudinal axis of the half-mold A, connect the corresponding

outer ends of said rods b and arms b' and form guides on which a movable part of the mold A' , similar in size and form to the fixed part A , has sliding connections, said two parts A and A' being in axial alinement. Said sliding connection comprises the yoke-pieces F , which encircle the part A' and have guide-apertures through which the guide-rods b^2 pass. If it is desired to heat the movable part, a tubular apertured ring G , connected by the pipe g to a flexible tube g' , may be used, g^2 representing a flexible efflux-pipe.

The parts of the mold may be of any suitable material, preferably of copper on account of its high heat conductivity. The mold-face a^3 of each part is shown as a concave hemisphere. This, obviously, may be of any desired form and the material may be anything suitable, such as porcelain. While the mold-face, so far as described, is fixed in the mold part, it may be made removable therefrom, so as to readily and quickly change the design of the mold. A convenient form of such a device is shown in Fig. 9, wherein the mold-face, herein shown as conical, has engagement by interior screw-threads a^6 with the wall a' of the mold, which permits of quick replacing of said face. In Fig. 9 there is also shown another form of hot-water-feed pipe G , which discharges against the upper part of the mold-face near its edge.

In Fig. 8 a vertical type of mold embodying the invention is illustrated. In this form of device the fixed part A of the mold is secured directly to the frame C , while the movable part A' is suitably secured in vertical alinement over said fixed part by a yoke F , which has sliding connection with a guide. Said guide is secured to said frame C parallel to the axis of the mold. A set-screw I may be used to clamp the part A' in any position desired. Another form of heating device which may be used is also illustrated in Fig. 8. An electrical conductor K from a suitable generating source leads through a controlling-switch k to a coil of high-resistance wire k' , which lies against the rear of the mold-face. Said resistance-wire, heated by the electric current, heats the mold-face.

The operation of the device is obvious. The parts are separated, a piece of ice inserted, and the mold is closed thereon, the heating of the faces and applied pressure shaping the ice into the desired design. The use of sharpened engaging edges and the heating thereof to a higher temperature than the mold-face, which may be accomplished, as shown, by having the hot water impinge near said edges first, enable the mold to quickly cut

large pieces of ice and mold them to the size 60 and design required.

We claim as our invention—

1. A mold for shaping ice, comprising two separable parts having recessed mold-faces and engaging edges and means for heating 65 said edges.

2. A mold for shaping ice, comprising two parts having recessed mold-faces, and means for heating said parts, and connections between said parts for opening and closing the 70 mold.

3. A mold for shaping ice, comprising two parts, either or each of said parts having a hollow chamber adjacent to the mold-face, and means within said chamber for heating 75 said mold-face.

4. A mold for shaping ice, comprising two parts having engaging edges, either or each of said parts having a hollow chamber adjacent to said edges, and means within said chamber for heating 80 said edges.

5. A mold for shaping ice, comprising two parts, either or each of said parts having a hollow chamber adjacent to the mold-face, and means for circulating hot water through 85 said chamber.

6. A mold for shaping ice, comprising two parts, either or each of said parts having a hollow chamber adjacent to the mold-face, a hot-water-feed pipe in said chamber discharging 90 against the wall adjacent to said mold-face, and an efflux-pipe from said chamber.

7. A mold for shaping ice, comprising two parts having engaging edges, either or each of said parts having a hollow chamber adjacent to the mold-face and said edges, a hot-water-feed pipe in said chamber discharging 95 against the walls adjacent to said edges, and an efflux-pipe leading from said chambers.

8. A mold for shaping ice, comprising two 100 parts each having a die-face detachably secured therein, and means for heating the die-face.

9. A mold for shaping ice, comprising a frame, a part mold secured to said frame, a 105 part mold having movable connections with said frame whereby said mold may be closed, and means for heating one or both of said part molds.

In testimony that we claim the foregoing as 110 our invention we affix our signatures, in presence of two witnesses, this 24th day of July, A. D. 1900.

HARRY A. MACCLYMENT.
